UNITED STATES PATENT OFFICE.

SCHUYLER W. ZENT, OF EVANSVILLE, INDIANA, ASSIGNOR TO THE ZENT AUTOMOBILE MANUFACTURING COMPANY, OF BELLEFON-TAINE, OHIO.

DEVICE FOR EFFECTING THE RADIATION OF HEAT.

No. 826,008.

Specification of Letters Patent.

Patented July 17, 1906.

Application filed February 15, 1904. Renewed December 27, 1905. Serial No. 293,500.

To all whom it may concern:

Be it known that I, SCHUYLER W. ZENT, a citizen of the United States, residing at Evansville, county of Vanderburg, and State 5 of Indiana, have invented certain new and useful Improvements in Devices for Effecting the Radiation of Heat, of which the following is a specification.

My invention relates to a method for effecting the rapid radiation of heat from objects exposed to a high temperature, and especially to reducing the temperature of internal-combustion cylinders.

The object of my invention is to provide 15 means for the reduction of such temperature that will combine lightness of weight with effectiveness. I accomplish this result by means of heat-conducting fins, which are attached to and radiate from the outside surface 20 of the cylinder.

In the drawings which form a part of this specification, Figure 1 is a section of the surface of a cylinder, showing a number of my heat-radiating fins in position. Fig. 2 is a 25 section of Fig. 1 on line XX. Fig. 3 is also a section of the cylinder, showing a fin and corking-strip before the fin has been permanently secured in the cylinder. Fig. 4 is a 30 section of a metal sheet, showing ragged edges D on the fins; and Fig. 5 is a transverse section of the cylinder.

A represents the dovetailed grooves which are made in the circumference of the cylinder. I extend these dovetailed grooves longitudinally of the cylinder; but should I desire I may extend them completely around the cylinder, and particularly are these methods applicable to the head of the cylinder.

B is the fin, which is secured in A. These 40 fins are preferably made in metal sheets out of a flat piece of metal sawed at the distance desired, as shown in Fig. 4. This sawing is done in such manner as to leave the edges of the fins rough or corrugated and extends to 45 about the outside surface of the cylinder. I also groove the sides of these fins by pressing, cutting, rolling, or any other desirable method. By having these fins roughened on the edges and grooved on the sides I greatly 50 increase their radiating-surface.

C is a strip of narrow heat-conducting metal, which is placed alongside the lower ends of the fins in aperture A.

To apply my invention to the cylinder, I first make the proper groove A in the cylinder. I then place my sheet of heat-conducting metal, sawed as above described, in the aperture A, one end being in the groove and the other radiating from the cylinder. I then place the heat-conducting metal strip C in the aperture A alongside the lower end of B, as shown in the first fin in Fig. 5. I then cork or tamp C down securely, and this causes the groove A to be entirely filled, thus holding fin B securely in A, as shown in second fin in Fig. 5. I twist the fins, as shown in Figs. 1 and 2 and in the third fin in Fig. 5, to give more free circulation to the air. As the cylinder becomes heated the fins in contact therewith receive a portion of said heat and 70 radiate it into the surrounding atmosphere. While I may have the aperture A any desirable shape, I find that by having it as shown the heat radiation is materially increased.

Having fully described my invention, what 75 I claim as new, and desire to secure by Letters Patent, is—

1. In a device for effecting the radiation of heat, the combination with a surface subject to heat effects, having grooves which are undercut in their inner portions, of heat-radiating members seated in said grooves in continuation along the length of said grooves, and projecting freely beyond the surface aforesaid, and independent strips tamped or forced into one side of said grooves alongside the heat-radiating members which press the latter into the opposite undercut portions of the grooves.

2. In a device for effecting the radiation of heat, the combination with a surface, subject to heat effects, having undercut grooves, of heat-radiating fins twisted at their base and seated in said grooves and projecting from the surface aforesaid, and independent strips tamped or forced into one side of said grooves alongside the heat-radiating fins which press the latter into the opposite undercut portions of the grooves and themselves fill the remaining undercut portions of the grooves.

In testimony whereof I hereunto affix my signature in the presence of two witnesses.

SCHUYLER W. ZENT.
